FASTENER

James F. Kennedy, Hartford, Conn.

Application May 19, 1938, Serial No. 208,787

6 Claims. (Cl. 24—152)

This invention relates to fasteners and is particularly adapted for a device which is intended to be used as a fastener for the blankets of infants' beds.

The primary object of the invention is to provide a device whereby blankets may be securely fastened to the mattress of a bed in an easy and convenient manner.

A further object of the invention is to provide such a device which cannot easily become accidentally detached from its fastening position, and a further object is to provide a fastener, of the character to be hereinafter described, which cannot cause injury.

Further objects and advantages of my invention will be apparent from the following description and from the drawing in which:

Figure 1 is a view in central vertical section of a fastener embodying my invention.

Figure 2 is a bottom view of the same, in elevation.

Figure 3 is a view of the said fastener partly in section and showing one application in the use thereof.

As illustrated in the drawing, my improved fastener consists of a helical, or screw shaped, wire pin 5 having a sharp point 6. The said pin is fastened, in any suitable manner, to a shaft 7 which is provided with a knob 8 at the top thereof and a clamping disc, or plate 9, is mounted on said shaft adjacent to the top of the pin 5. The said shaft is slidably mounted in a guard cap 10 and extends through an opening in the top thereof which is surrounded by a flange 11, for guiding said shaft longitudinally to the axis of said guard, and the bottom of the guard is provided with an outwardly extending flange 12.

A compression spring 13 is mounted between the top of said guard and said knob 8 and fits into a recess 8—a in the bottom of the knob. The said spring operates to force the guard 10 over the pin 5 so as to retract the same, into the position illustrated in Figure 1, and thereby shield the pin point 6 against accidental contact therewith.

My improved fastener may be used, as illustrated in Figure 3, in which, the numeral 14 denotes the mattress of a bed, 15 a sheet covering the said mattress and 16 denotes the blankets of the bed. When so used, the fastener is first placed upon the top of the blankets 16 while it is in the normal condition illustrated in Figure 1. The knob 8 is then forced downwardly and turned in a clockwise direction. This causes the point 6 to pierce through the blankets and the sheet, and

thread itself into the mattress 14 as clearly illustrated.

When the said pin has been threaded into the mattress to its full extent, the clamping disc 9 will come into contact with the top of the blankets and clamp them firmly against the mattress. The guard 10 will be forced downwardly with the flange 12 surrounding the said clamping disc and thereby serve to additionally clamp the blankets; thus securely fastening them against displacement upon the mattress.

Should the fastener become accidentally disengaged from its fastening position, such as by a child in the bed tampering with the fastener or accidentally disengaging it while asleep, the pin 5 would be retracted, by means of the spring 13, into the guard 10 and the point 6 will be shielded thereby. Thus, any possibility of the child coming into contact with the sharp point, will be eliminated so that he cannot be injured thereby.

The said point will, likewise, become shielded by retracting into the guard 10, when the fastener is normally detached from its fastening position.

It will be understood from the above description, that while I have described my improved fastener particularly as intended for fastening blankets to a mattress, my invention may also be applied, without departing from the scope of the appended claims, wherever it is desired to provide a fastener in which a sharp point thereon is shielded so that it cannot cause injury.

I claim:

1. A fastener comprising a spirally shaped pin having a sharp point, a clamping plate positioned above said pin and movable therewith, a shaft connected to said pin, a handle on said shaft, a guard adapted to receive said pin and slidably mounted on said shaft, and means comprising a spring between and in contact with said handle and guard for moving said guard into position to shield said pin thereon against accidental contact therewith.

2. A fastener comprising a spiral pin having a sharp point, a stem comprising a shaft for carrying said pin, a handle on said shaft, a clamping plate secured to the said shaft and on a plane below the top of said pin, a guard slidably mounted on said shaft and adapted to cover said pin and clamping plate and to contain the said point against accidental contact therewith and means comprising a spring on said shaft for forcing said guard into operative position relative to said pin.

3. A fastener of the character described com-

55

prising a spiral wire pin having a sharp point thereon and mounted to the end of a stem, a clamping plate disposed below the top of said pin, a knob or handle mounted upon the end of said stem, a guard slidably mounted on said shaft and having a wall surrounding said pin, and spring means between the top of said guard and the bottom of said knob for retaining said guard in position to contain said pin therein and shield said point against accidental contact therewith and to force said guard into contact with the surface of a member to be fastened by said fastener when the said pin is imbedded therein.

4. A fastener of the character described comprising a stem, a pin projecting from the end of said stem, a clamping member mounted to said stem, a guard slidably mounted on said stem and adapted to overlie said member and pin, a knob on the end of said stem having a recess therein, and a spring fitting within said recess and against said guard for normally retaining said guard in

operative position for preventing contact with the end of said pin.

5. A fastener comprising a stem having a pin secured thereto, a guard slidable on said stem and adapted to prevent accidental contact with the end of said pin, a knob on said stem for rotating said pin and having a recess in the bottom thereof, and a spring adapted to be contained within said recess and positioned between said knob and guard for normally retaining said guard in operative position.

6. A fastener of the character described comprising a stem having a pin extending therefrom, a guard slidably mounted on said stem having a collar surrounding the stem, a spring surrounding said stem and collar for retaining said guard in operative position to prevent accidental contact with the end of said pin, and a handle on said stem having a recess in the bottom thereof adapted to receive the said spring and collar. 20
